Mr. H. Campbell,
ATTORNEY.

UNITED STATES PATENT OFFICE

JOSEPH DREYFUSS, OF NEW YORK, N. Y., ASSIGNOR TO EASTERN TOOL & MFG. CO., OF BLOOMFIELD, NEW JERSEY

GARMENT HANGER

Application filed July 25, 1930. Serial No. 470,634.

This invention relates to an improved garment hanger which has a body portion made of wire, has a hook secured so as to swivel on the body portion, has means for preventing dresses from slipping off the arched part of the hanger and one that holds a coiled helical spring which is out of the way and which is used for holding moth balls or the like.

The object of the invention is to provide a hanger of few parts and which utilizes 10 depressions in the arched part not only to prevent the straps of dresses from slipping off the hanger but to act as supports or 15 holders for the spring or other form of ball holder.

Another object of the invention is to provide a hanger with one wire forming the body portion, a wire formed into a hook, and a clip to connect the ends of the wire of the 20 body portion with the end of the hook, thus also forming a swivel connection for the hook. This makes a sturdy and cheap construction.

The invention is illustrated in the accompanying drawing in which Figure 1 is a side 25 view of a garment hanger embodying my invention. Figure 2 is a section on line 2—2 in Figure 1. Figure 3 is an enlarged section on line 3—3 in Figure 1.

The body portion of the hanger is formed 30 with an arched part for fitting the inside of coats. The form I show consists of a wire which forms a bottom strand 10 which is bent at its ends to form the end strands 11 and 12 35 and then inwardly as at 13 and 14 to form the arched part. The ends 15 and 16 of the wire are opposed. I connect them by a clip 17 which is usually made of sheet metal and is bent around the ends 15 and 16 of the wire. 40 A good way to prevent separation of the wires is to flatten them as at 18 and the clip is widened to receive these flattened ends. The clip 17 is perforated to receive the headed end 19 of the shank 20 of the hook 21. This member is also made of wire, in the preferred 45 form.

Under the arched part I place a holder for 50 moth balls or similar insecticide. The holder is preferably in the form of a helical or coiled spring 22 with ends supported by inwardly

and downwardly inclined loops 23 which 55 form depressions 24. These depressions act to receive the shoulder straps of dresses to prevent them from slipping off the arched part of the hanger. The spring 22 has its end 25 hooked around the loops 23 and then 60 bent inward at 26 to extend across the passage in the spring in which the moth balls 27 are placed. The spring wire is light and the holder 22 is easily opened at the ends by 65 bending the ends 26 while moth balls are placed into or removed from the holder. This prevents the distortion of the wire coils which would result if the balls were forced in between coils of the holder.

Various changes can be made in the shape 65 of the parts without departing from the scope of the invention as embodied in the claims.

I claim:—

1. A garment hanger comprising a wire 70 bent to form an arched body portion with its ends abutting in the center, a hook including a shank and a perforated clip securing the two ends of the wire together and forming a swivel connection for the shank of the hook, 75 the arched part having a depressed open loop near each end and a coiled spring with ends supported by the said loops, said ends extending across the open ends of the spring to form resilient closures for said spring. 80

2. A garment hanger comprising a curved wire supported at the centre, a coiled spring, the wire having depressed inwardly inclined open loops on both sides of the centre, the spring being supported at its ends by the 85 loops and which loops also form depressions for receiving the straps of garments.

3. A garment hanger comprising a wire bent to form a bottom strand and an arched 90 top strand with the ends of the wire opposed and flattened, a hook having a headed shank thereon, a clip to connect the flattened ends of the wire and receive the shank of the hook, the arched wire having inwardly directed depressions near its ends, and a helical spring 95 supported under tension by said wire at the depressions.

In testimony whereof I affix my signature.
JOSEPH DREYFUSS.
